Primary Examiner — Selina Sikder(74) *Attorney, Agent, or Firm* — Rankin, Hill & Clark LLP(57) **CLAIM**

We claim the ornamental design for a push switch, as shown and described.

DESCRIPTION

FIG. 1 is a front elevation view of a push switch.

FIG. 2 is a rear elevation view thereof.

FIG. 3 is a right side elevation view thereof.

FIG. 4 is a left side elevation view thereof.

FIG. 5 is a top plan view thereof.

FIG. 6 is a bottom plan view thereof.

FIG. 7 is a cross-sectional view thereof, taken along the line 7-7 in FIG. 5.

FIG. 8 is a cross-sectional view thereof, taken along the line 8-8 in FIG. 5; and,

FIG. 9. Is a perspective view thereof.

The article is used, for example, for small electronic devices, such as mobile phones.
